(57) **CLAIM**

The ornamental design for a vehicle top carrier, as shown and described.

DESCRIPTION

FIG. 1 is a perspective view of a vehicle top carrier;

FIG. 2 is a top view thereof;

FIG. 3 is a side view thereof;

FIG. 4 is another side view thereof;

FIG. 5 is a bottom view thereof;

FIG. 6 is a front view thereof; and,

FIG. 7 is a rear view thereof.

The stippling and shading lines shown in the drawing(s) represent the approximate three-dimensional contour of the design, and are not intended to indicate surface decoration.

1 Claim, 3 Drawing Sheets

FIG.2
